F. O. BENNEWITZ

SPIRIT LEVEL

Filed March 1, 1922

Inventor,
Fred O. Bennewitz.
By Hazard Miller Atty's.

UNITED STATES PATENT OFFICE.

FRED O. BENNEWITZ, OF LOS ANGELES, CALIFORNIA.

SPIRIT LEVEL.

Application filed March 1, 1922. Serial No. 540,157.

To all whom it may concern:

Be it known that I, FRED O. BENNEWITZ, a citizen of the United States, residing at Los Angeles, in the county of Los Angeles 5 and State of California, have invented new and useful Improvements in Spirit Levels, of which the following is a specification.

My invention relates to improvements in spirit levels, the principal objects of my invention being to provide a relatively simple, practical and efficient device that is capable of being easily and quickly applied to a straight edge bar, a straight rail, the blade of a T-square or other similar object, and 15 which device carries a spirit level thus making it possible to conveniently arrange the device on a straight edge bar or rail and the associated parts utilized for leveling purposes in building operations.

It will be understood that the ordinary forms of spirit levels include bars or rails that are generally two or three feet in length and such forms of levels cannot always be conveniently carried and handled.

I propose to provide a relatively small, compact device that may be conveniently carried in a tool box or in the pocket and which device is constructed so that it may be easily and quickly applied to or removed 30 from a straight edge bar or the like and which latter takes the place of the bar or rail that forms the body of the ordinary spirit level.

With the foregoing and other objects in view, my invention consists in certain novel features of construction and arrangement of parts that will be hereinafter more fully described and claimed and illustrated in the accompanying drawings, in which—

Fig. 1 is a perspective view of a spirit level of my improved construction.

Fig. 2 is a horizontal section taken approximately on the line 2—2 of Fig. 1.

Fig. 3 is a transverse section taken approximately on the line 3—3 of Fig. 1.

Fig. 4 is a side elevational view of a modified form of the spirit level.

Referring by numerals to the accompanying drawings which illustrate a practical embodiment of my invention, 10 designates a substantially rectangular plate of suitable material such as metal, wood or hard rubber, and formed in one of the side faces of said plate is a longitudinally disposed channel 11.

Formed in the side face of this channel is a longitudinally disposed recess 12 and ar-

ranged therein is a bow spring 13 having one end secured in any suitable manner to plate 10 and the opposite end of said spring being free to move lengthwise of the recess 12. 60

Secured to and projecting upwardly from the central portion of the top of plate 10 is a neck member 14 that serves as a support for a longitudinally disposed housing 15, the central portion of which is cut away to 65 form an opening 16 and seated in said housing is a tube 17 of glass containing a body of suitable liquid and an air bubble 18.

Secured in any suitable manner to the upper portion of plate 10 and overlying the channel 11 is a plate 19 that may have the same length and width as plate 10. When the device is detached from a straight edge or rail the central portion of spring 13 bears against the inner face of plate 19 and when 70 the device is positioned upon the straight edge the spring is forced into the groove or recess 12 as shown by dotted lines in Fig. 2, thereby creating sufficient tension to firmly retain the leveling attachment in position 75 upon the straight edge or rail.

Thus the device which is very compact and capable of being carried in the pocket or in a small tool box may be conveniently arranged on a straight edge or bar and utilized 80 for leveling purposes in any building operation.

In the modified construction illustrated in Fig. 4 the end portions of the plate forming the main body of the device are extended 90 upward as designated by 20 and the bubble containing glass tube has its ends seated in these upward extensions. Secured to the tops of the extensions 20 and overlying the exposed portion of the bubble containing 95 tube is a plate 21, preferably of metal.

Thus it will be seen that I have provided a simple, practical and convenient spirit level attachment that may be readily applied to or removed from a body such as a 100 straight edge rail or the like.

It will be understood that minor changes in the size, form and construction of the various parts of my spirit level may be made and substituted for those herein shown 105 and described without departing from the spirit of my invention, the scope of which is set forth in the appended claims.

I claim as my invention:

1. A spirit level comprising a plate having a recess formed in one face, a second plate removably secured to, but spaced from,

the first mentioned plate and overlying said recess, a spring secured to the first mentioned plate and arranged within said recess, and a bubble containing tube arranged on 5 and carried by the first mentioned plate.

2. In a spirit level, an L-shaped plate having a longitudinally-disposed recess formed in one leg, a spring secured to said plate

and arranged within said recess, a second plate removably secured to the other leg of 10 said plate and overlying the recess to form a channel therebetween and a bubble containing tube carried by the first mentioned plate.

In testimony whereof I have signed my name to this specification.

FRED O. BENNEWITZ.
